UNITED STATES PATENT OFFICE.

EUGÈNE SCHNEIDER, OF PARIS, FRANCE, ASSIGNOR TO SCHNEIDER & CIE., OF PARIS, FRANCE, A LIMITED JOINT-STOCK COMPANY OF FRANCE.

APPARATUS FOR EXTENDING THE LIMITS OF ELEVATION OF WHEELED GUNS.

1,310,147.

Specification of Letters Patent. Patented July 15, 1919.

Application filed September 13, 1918. Serial No. 253,989.

To all whom it may concern:

Be it known that I, EUGÈNE SCHNEIDER, a citizen of the French Republic, and a resident of 42 Rue d'Anjou, Paris, France, have 5 invented a new and useful Improvement in Apparatus for Extending the Limits of Elevation of Wheeled Guns, which invention is fully set forth in the following specification.

10 This invention has for its object to provide an improved apparatus applicable to wheeled guns for the purpose of extending their limits of elevation.

The improved apparatus consists substantially of a trail head comprising two pairs of bearings arranged at different levels for the trunnions of the gun cradle, the axes of these bearings being situated on one and the same arc of a circle having for its center the 20 axis of the driving pinion or pinions of the elevating sector or sectors. The improved apparatus allows of bringing the trunnions of the gun cradle alternately into the lower bearings or into the upper bearings without 25 this change of position affecting appreciably the relative position of the parts of the elevating mechanism of the gun.

Some practical constructions embodying this invention are illustrated by way of example in the accompanying drawings in 30 which:

Figure 1 is a side elevation partly in section of a trail gun carriage provided with the improved apparatus, the gun cradle being shown with its trunnions situated in the lower bearings of the improved trail head.

Fig. 2 is a similar view wherein the gun cradle is shown with its trunnion situated in the upper bearings for the purpose of firing at high angles of elevation.

Fig. 3 is a cross section drawn to a larger scale on the line III—III of Fig. 2.

Figs. 4 and 5 are respectively a partial side elevation and a cross-section on the 45 line V—V of Fig. 4 of a modification wherein the cradle trunnions are mounted in bearing steps.

Figs. 6, 7 and 8 illustrate a second practical construction embodying the invention.

50 Fig. 6 is a side elevation, partly in section, of the improved trail head with double headings.

Fig. 7 is a corresponding half plan, and Fig. 8 is a cross-section on the line VIII—VIII of Fig. 6.

Figs. 9 and 10 show in side elevation and cross-section respectively a construction wherein one or both cheeks of the trail head are provided with a rack projecting at the side of the track that connects the trunnion bearing surfaces.

A is a gun barrel of any known type, adapted to recoil in a gun cradle B. C is the carriage trail. The elevating mechanism comprises the known construction of one or 65 two toothed sectors D carried by the cradle engaging with coöperating pinions E fixed on a shaft e journaled in the cheeks of the trail or in a stay C¹ connecting the cheeks.

In the first modification the two bearings 70 situated at different levels consist, as regards each cradle trunnion b, of two bearing surfaces F and F¹ formed at the respective ends of a circular track G having its center in the geometric axis of the shaft e. It is 75 to be understood that the curvature of the bearing surfaces F and F¹ must be such that the axis of the trunnions b, when situated in one or the other of the said bearing surfaces, shall always be in one and the same arc of 80 a circle struck from e, as its center. The upper bearing member or cap-square I which completes the bearing of each trunnion is formed in a cap covering both the two bearing surfaces F, F¹, and the connecting track 85 G. When the gun is arranged for firing at low angles of inclination or where the convenient limits of elevation are limited by the positions indicated in Fig. 1 in full lines and dot and dash lines respectively, the gun can 90 be quickly adapted for firing at high angles of elevation by proceeding as follows:

The cap in which the cap-square I is 95 formed, and which may be fixed to the trail head by bolts i or any other suitable devices, is removed. The muzzle end of the gun barrel is raised and the trunnions b of the cradle are moved along the connecting tracks G until they rest in the upper bearing surfaces F¹. The cap comprising the 100 cap-square I can then be turned around through 180° relatively to the first position and fixed therein, as indicated in Fig. 2. By raising the trunnions through the height

H with an angular displacement around the shaft e, it is possible to effect this maneuver without affecting the parts of the elevating mechanism of the gun. In the new position 5 of the trunnions, the limits of elevation have been extended exactly by the value of the angle through which the cradle trunnions have been turned in raising them.

The toothed sector or sectors D may as 10 shown in Fig. 3, be guided in a slideway j formed in the underside of a half ring J that is movable about the cylindrical stay C¹, between collars c¹ on the latter. By this means the sectors D are perfectly guided in 15 both positions of the trunnions b.

In Figs. 4 and 5 is shown a modification wherein the cradle trunnions b are mounted in bearing steps K whose supporting surfaces k are made concave to correspond with 20 the convexity of the track G. It is to be understood that the cap I forming the cap-square is in this case suitably shaped to cover the special bearing step K. In the rising and descending movements of the 25 cradle for passing from the position shown in Fig. 1 into the position shown in Fig. 2, or vice versa, the steps K are slid along the track G instead of sliding the trunnions b directly along said track.

30 In the construction shown in Figs. 6, 7 and 8, two cap-squares I and I¹ are provided for each trunnion b at the ends of one and the same cap which is hinged to the trail head by means of a pivot pin L and is thus capable of being raised to allow of 35 shifting the trunnions from the lower trunnion bearing surfaces F into the upper trunnion bearing surfaces F¹, and vice versa.

The cap may be fixed in the turned down 40 position by means of a key M or any other suitable device. The caps are preferably provided with two nibs I² for engagement in the trail head in the neighborhood of the lower bearing surfaces F.

45 As shown in Figs. 9 and 10, one of the cheeks of the trail head or both cheeks may be provided with a rack N projecting at the side of the track G that connects the bearing surfaces. Like the said track, the said rack 50 has its center of curvature on the axis e. O is a short shaft carrying a pinion P and adapted to be rotated by means of the crank Q. After having removed or raised the corresponding cap-square, the shaft O can be 55 inserted in a bearing provided in one of the trunnions for the purpose of shifting the trunnions b. When this operation has been effected, the entire device O—P—Q is removed, and the cap-square is replaced in the 60 suitable position.

Having now described my invention what I claim as new and desire to secure by Letters Patent is:—

1. An apparatus for extending the limits 65 of elevation of wheeled guns, consisting of

a trail head comprising two pairs of bearings at different levels for the trunnions of the gun cradle, the axes of said bearings being situated in one and the same arc of a circle having its center in the axis of the actuating pinion or pinions of the elevating sector or sectors, the said cradle trunnions being then capable of being shifted into one or the other pair of bearings for firing at low or high angles of elevation by 70 simply raising the cradle and the gun barrel as a whole, without affecting in any way the parts of the gun or its elevating mechanisms.

2. In apparatus for extending the limits 80 of elevation of wheeled guns, a trail head comprising two pairs of bearings at different levels for the trunnions of the gun cradle, said bearings having their axes in an arc of a circle having its center in the axis of the actuating pinion or pinions of the elevating sector or sectors, 85 and a circular track connecting the bearings for each trunnion, said track having its center in the axis of said pinion or pinions.

3. In apparatus for extending the limits 90 of elevation of wheeled guns, in combination with the trunnions of the gun cradle, a trail head comprising two pairs of bearings at different levels for said trunnions, said bearings having their axes in an arc of a circle 95 having its center in the axis of the actuating pinion or pinions of the elevating sector or sectors, and means for shifting said trunnions from one pair of bearings to the other.

4. In apparatus for extending the limits 100 of elevation of wheeled guns, in combination with the trunnions of the gun cradle, a trail head comprising two pairs of bearings at different levels for said trunnions, said 105 bearings having their axes in an arc of a circle having its center in the axis of the actuating pinion or pinions of the elevating sector or sectors, a circular track connecting the bearings for each trunnion, said track 110 having its center in the axis of said pinion or pinions, a rack concentric with said tracks, and a pinion coöperating with said rack for shifting said trunnions from one pair of bearings to the other.

5. In apparatus for extending the limits 115 of elevation of wheeled guns, in combination with the trunnions of the gun cradle, a trail head comprising two pairs of bearings at different levels for said trunnions, said bearings having their axes in an arc of a circle 120 having its center in the axis of the actuating pinion or pinions of the elevating sector or sectors, a circular track connecting the bearings for each trunnion, said track having its center in the axis of said pinion or pinions, a rack concentric with said tracks, a pinion adapted to coöperate with said rack 125 for shifting said trunnions from one pair of bearings to the other, and operating means 130

for said pinion, said pinion and operating means being detachably engageable with one of said trunnions.

6. In apparatus for extending the limits 5 of elevation of wheeled guns, in combination with the trunnions of the gun cradle, a trail head comprising two pairs of bearings at different levels for said trunnions, said bearings having their axes in an arc of a circle 10 having its center in the axis of the actuating pinion or pinions of the elevating sector or sectors, and pivoted means for retaining said trunnions in either of said bearings.

7. In apparatus for extending the limits 15 of elevation of wheeled guns, in combination with the trunnions of the gun cradle, a trail head comprising two pairs of bearings at different levels for said trunnions, said bearings having their axes in an arc of a circle 20 having its center in the axis of the actuating pinion or pinions of the elevating sector or sectors, a circular track connecting the bearings for each trunnion and having its center in the axis of said pinion or pinions, and a 25 single member pivoted to said trail head for retaining each trunnion in either of its bearings.

8. In apparatus for extending the limits 30 of elevation of wheeled guns, in combination with the trunnions of the gun cradle, a trail head comprising two pairs of bearings at different levels for said trunnions, said bearings having their axes in an arc of a circle 35 having its center in the axis of the actuating pinion or pinions of the elevating sector or

sectors, means for shifting said trunnions from one pair of bearings to the other, and pivotal means for retaining said trunnions in either of said bearings.

9. In apparatus for extending the limits 40 of elevation of wheeled guns, in combination with the trunnions of the gun cradle, a trail head comprising two pairs of bearings at different levels for said trunnions, said bearings having their axes in an arc of a circle 45 having its center in the axis of the actuating pinion or pinions of the elevating sector or sectors, and a single member for retaining each trunnion in either of its bearings.

10. In apparatus for extending the limits 50 of elevation of wheeled guns, in combination with the trunnions of the gun cradle, a trail head comprising two pairs of bearings at different levels for said trunnions, said bearings having their axes in an arc of a circle 55 having its center in the axis of the actuating pinion or pinions of the elevating sector or sectors, a circular track connecting the bearings for each trunnion and having its center in the axis of said pinion or pinions, a single 60 member for retaining each trunnion in either of its bearings, and means for securing said member in trunnion-retaining position.

In testimony whereof I have signed this specification.

EUGÈNE SCHNEIDER.
